(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIGURE is a front view of a display screen or portion thereof with graphical user interface showing our new design.

The broken lines shown at the perimeter of the FIGURE illustrate portions of the display screen and form no part of the claim.
